THE NORRIS PETERS CO., PHOTO-LITHO., WASHINGTON, D. C.

UNITED STATES PATENT OFFICE.

ALFRED M. ACKLIN, OF PITTSBURG, PENNSYLVANIA.

CAR-HAUL.

SPECIFICATION forming part of Letters Patent No. 694,047, dated February 25, 1902.

Application filed November 25, 1901. Serial No. 83,609. (No model.)

To all whom it may concern:

Be it known that I, ALFRED M. ACKLIN, a resident of Pittsburgh, in the county of Allegheny and State of Pennsylvania, have invented a new and useful Improvement in Car-Hauls; and I do hereby declare the following to be a full, clear, and exact description thereof.

My invention relates to car-hauls, and has for its object to provide a simple and effective device for taking cars from a state of rest or from a slow speed and moving them along at a gradually-accelerated speed and to the same speed as the hauling-chain.

My invention consists, generally stated, in the novel arrangement, construction, and combination of parts, as hereinafter more specifically set forth and described, and particularly pointed out in the claims.

To enable others skilled in the art to which my invention appertains to construct and use my improved car-haul, I will describe the same more fully, referring to the accompanying drawings, in which—

Figure 1 is a side view of my improved car-haul. Fig. 2 is a plan view of the same. Fig. 3 is an enlarged detail view of the receiving end of the hauling-chain, showing the device ready to engage with the car; and Fig. 4 is a like view showing the device in position after it has moved the car to the hauling-chain.

Like symbols of reference herein indicate like parts in each of the figures of the drawings.

As illustrated in the drawings, the tracks are shown at 1 and are provided with the portions 2 2' thereon, with the inclined portions 3 between, and upon these tracks 1 the cars 4 are adapted to travel. Between the inclined portion 3 of the tracks 1 is preferably located the uphaul-chain 5, which is provided with a series of hooks or projections 6 on one side 5' thereof for engaging with a bar 4' on the cars 4 and passes around sprocket-wheels 7 7', which are mounted on shafts 8 8', and said chain 5 being guided by the guide-roller 9, located adjacent to the upper sprocket-wheel 7' and mounted on the shaft 10.

Mounted loosely around the shaft 8 for the lower sprocket-wheel 7 is the drum 11, which is provided with the cam-face 12 thereon, and on one side of this drum 11 and connected

thereto is located the arm 13, which is also loosely mounted around the shaft 8 and extends some distance beyond the outer or enlarged portion 12' of the cam-face 12 on the drum 11, as at 13', and this projecting portion 13' is adapted to engage with hooks or projections 6', formed on the other side 5' of the uphaul-chain 5 and opposite the hooks or projections 6 on the side 5' of said chain 5.

Extending preferably between the portion 2 of the tracks 1 is the sliding or reciprocating frame or bar 14, which is adapted to travel upon slides or tracks 14' by means of rollers 15 thereon and has a yielding hook 16 pivoted in the front end 14'' thereof, as at 17, the outer end 16' of which is adapted to project some distance above the bar 14. Projecting down from the reciprocating bar 14 is the lug 18, which is adapted to be secured to a rope 19, having one of its ends connected to a drum 20 on a shaft 21, while its opposite end is provided with a weight 22 thereon, and such rope 19 passes over a sheave 23, mounted on a shaft 23'. A smaller drum 24 is mounted upon the shaft 21, and a rope 25 is connected thereto and to the smaller portion 12'' of the cam-face 12 on the drum 11.

The use and operation of my improved car-haul are as follows: Power being applied to the upper shaft 8' in any suitable manner will act to turn said shaft 8' and with it the uphaul-chain 5, which passes around the sprocket-wheels 7 7' on the shafts 8 8', respectively, thereby moving with said chain 5 the wheel 7' and said shaft 8' as well as the wheel 7 and said shaft 8. Each of the cars 4 is brought at a slow rate of speed along the portion 2 of the tracks 1, and passing over the reciprocating bar 14 the bar 4' on the cars 4 will strike the projecting end 16' of the pivoted hook 16 thereon and depress such end 16', so that the car will pass over said end 16' and be brought to position in front of the pivoted hook 16, and as the uphaul-chain 5 is moving continuously around the sprocket-wheels 7 7' one of the hooks or projections 6' on the side 5'' of said chain 5 will act to engage with the projecting portion 13' on the arm 13, which will cause said arm 13 to revolve in the direction of the arrow and with it the drum 11 connected thereto. When the arm 13 and drum 11 have thus started to revolve by the

engagement of one of the hooks or projections 6' on the chain 5 with the end 13' on said arm 13 and one of the cars 4 has passed over the reciprocating bar 14 and end 16' of the 5 pivoted hook 16 thereon, so as to be brought to a state of rest or is traveling at a slow speed on the portion 2 of said tracks 1, the revolving of said drum 11 and arm 13 engaging with the hook 6' will act to unwind the rope 25 10 from around the small drum 24 on the shaft 21 and wind the same around the cam-face 12 on the drum 11, so causing the rope 19, connected to the reciprocating bar 14, to be wound around the large drum 20 on the shaft 15 21 as such shaft 21 and small drum 24 are turned in the direction of the arrow by the rope 25, and thereby move the bar 14 in the direction of the arrow. As the reciprocating bar 14 is thus moved by the winding of the rope 19 20 around the drum 20 the end 16' of the pivoted hook 16 thereon will strike against the bar 4' on said car 4 and cause said car to be moved along the portion 2 on said tracks 1 from a state of rest or a slow speed to a speed gradually and continually increasing as the rope 25 25 is wound around the cam-face 12 on the drum 11 and the rope 19 is wound around the drum 20, and when the drum 11 and arm 13 have been raised to the position shown in Fig. 4 30 the car 4 will have been brought along the portion 2 of the tracks 1 to the uphaul-chain 5 from a state of rest or slow rate of speed by a gradual and continual increase of speed to the speed of the uphaul-chain 5, where it will 35 be caught by one of the hooks 6 on the side 5' of the chain 5 engaging with the bar 4' on said car 4 and carried up the inclined portion 3 of said tracks 1 by such hook 6 on the chain 5. After the hook 6 on the chain 5 has engaged with the bar 4' on the car 4 and has started to move said car up the inclined portion 3 of the tracks 1 the hook 6' on said 40 chain 5 will be relieved from engagement with the end 13' of said arm 13 and such arm 13, 45 drum 11, and bar 14 will be pulled back by the weight 22 on said rope 19, connected to the bar 14, which will allow the rope 19 to unwind itself from around the drum 20 and the rope 25, connected to the drum 11, to 50 wind itself around the drum 24, so dropping or lowering the arm 13 and drum 11 down to the position shown in Fig. 3, ready to be again caught by one of the hooks 6' on said chain 5 and bringing the reciprocating bar 14 55 back to the position shown in said figure, ready to have the end 16' of the pivoted hook 16 on said bar 14 catch the bar 4' on another car 4 for another operation. After the cars 4 have traveled up the inclined portion 3 of 60 the tracks 1 by means of the hooks 6 on the uphaul-chain 5 and have reached the point adjacent to the sprocket-wheel 7' the hooks 6 on said chain 5 will become disengaged from the bars 4' on said cars 4 and such cars can 65 pass along the portion 2' of said tracks 1 to any place desired. As the uphaul-chain 5 is run continuously around the sprocket-

wheels 7 7', it will be evident that the drum 11 and arm 13 will be raised and lowered through the engaging and disengaging of the 70 arm 13 with the hooks 6' on said chain 5, and that the reciprocating bar 14 will be advanced and receded by the rope 19 connecting therewith and with the large drum 20 and by the rope 25 connecting the small drum 24 with the cam-drum 11, so that such bar 14 will always allow one of the cars 4 to pass over the same and over the end 16' of the pivoted hook 16 thereon and be in position for the end 16' of such hook 16 to engage with the bar 4' 80 on the car to advance the same from a state of rest or slow speed by a gradual and continual increased speed to that of the chain 5 and be caught by the hooks 6 on such chain and carried thereby up the inclined portion 3 85 of the tracks 1.

It will be obvious that the device for engaging with the cars to bring them from a state of rest or slow speed by a gradual and continual increased speed to that of the chain 90 95 can be placed outside of the tracks, if desired, and that under some conditions the uphaul-chain can be placed to one side or outside of the tracks and the hooks on such chain engage with the axle of the cars, while various other modifications in the construction and design of the various parts may be resorted to without departing from the spirit of the invention or sacrificing any of its advantages.

It will thus be seen that my improved car-haul is cheap and simple in its construction and operation, and by its use the heavy strain and jolting to the uphaul-chain and cars is overcome, as well as permitting a greater speed to be applied to the hauling-chain than 105 in the ordinary cases, with the result that a greater capacity may be had from a given weight of chain and power-transmission mechanism.

What I claim as my invention, and desire 110 to secure by Letters Patent, is—

1. A device for moving cars, consisting of a continuously-moving hauling-chain having hooks thereon for engaging with the car, and mechanism for bringing the car from a state 115 of rest or slow speed by a gradually-increased speed to that of the hauling-chain to be caught and hauled thereby.

2. A device for moving cars, consisting of a continuously-moving hauling-chain having 120 hooks thereon for engaging with the car, and mechanism for automatically engaging with the car to bring the same from a state of rest or slow speed by a gradually-increased speed to that of the hauling-chain to be caught and 125 hauled thereby.

3. A device for moving cars, consisting of a continuously-moving hauling-chain having hooks thereon for engaging with the car, and mechanism for engaging with the car to bring 130 the same from a state of rest or slow speed by a gradual and continual increased speed to that of the chain to be caught and hauled thereby.

4. A device for moving cars, consisting of a continuously-moving hauling-chain having hooks thereon for engaging with the car, and mechanism for automatically engaging with the car to bring the same from a state of rest or slow speed by a gradual and continual increased speed to that of the chain to be caught and hauled thereby. 5
5. A device for moving cars consisting of a continuously-moving hauling-chain having hooks thereon for engaging with the car, and mechanism engaging with said hauling-chain and car for bringing said car from a state of rest or slow speed by a gradually-increased speed to that of the chain to be caught and hauled thereby. 10
6. A device for moving cars, consisting of a hauling-chain having hooks thereon for engaging with the car, and mechanism for automatically engaging with said hauling-chain and car to bring said car from a state of rest or slow speed by a gradually-increased speed to that of the chain to be caught and hauled thereby. 15
7. A device for moving cars, consisting of a continuously-moving hauling-chain having hooks thereon for engaging with the car, and mechanism engaging with said hauling-chain and car for bringing said car from a state of rest or slow speed by a gradual and continual increased speed to that of the chain to be caught and hauled thereby. 20
8. A device for moving cars, consisting of a hauling-chain having hooks thereon for engaging with the car, and mechanism for automatically engaging with said hauling-chain and car to bring said car from a state of rest or slow speed by a gradual and continual increased speed to that of the chain to be caught and hauled thereby. 25
9. A device for moving cars, consisting of a hauling-chain having hooks thereon for engaging with the car, a sliding or reciprocating frame or bar for engaging with said car, and connections between said hauling-chain and bar for bringing said car from a state of rest or slow speed by a gradually-increased speed to that of the chain to be caught and hauled thereby. 30
10. A device for moving cars, consisting of a hauling-chain having hooks thereon for engaging with the car, a sliding or reciprocating frame or bar for engaging with said car, and connections between said hauling-chain and bar for automatically bringing said car from a state of rest or slow speed by a gradually-increased speed to that of the chain to be caught and hauled thereby. 35
11. A device for moving cars, consisting of a hauling-chain having hooks thereon for engaging with the car, a sliding or reciprocating frame or bar for engaging with said car, and connections between said hauling-chain and bar for bringing said car from a state of rest or slow speed by a gradual and continual increased speed to that of the chain to be caught and hauled thereby. 40
12. A device for moving cars, consisting of a hauling-chain having hooks thereon for engaging with the car, a sliding or reciprocating frame or bar for engaging with said car, and connections between said hauling-chain and bar for automatically bringing said car from a state of rest or slow speed by a gradual and continual increased speed to that of the chain to be caught and hauled thereby. 45
13. A device for moving cars, consisting of a hauling-chain having hooks thereon for engaging with the car, a sliding or reciprocating frame or bar, a yielding or pivoted hook on said bar for engaging with the car, and connections between said hauling-chain and bar for bringing said car from a state of rest or slow speed by a gradually-increased speed to that of the chain to be caught and hauled thereby. 50
14. A device for moving cars, consisting of a hauling-chain having hooks thereon for engaging with the car, a sliding or reciprocating frame or bar, a yielding or pivoted hook on said bar for engaging with the car, and connections between said hauling-chain and bar for automatically bringing said car from a state of rest or slow speed by a gradually-increased speed to that of the chain to be caught and hauled thereby. 55
15. A device for moving cars, consisting of a hauling-chain having hooks thereon for engaging with the car, a sliding or reciprocating frame or bar, a yielding or pivoted hook on said bar for engaging with the car, and connections between said hauling-chain and bar for bringing said car from a state of rest or slow speed by a gradual and continual increased speed to that of the chain to be caught and hauled thereby. 60
16. A device for moving cars, consisting of a hauling-chain having hooks thereon for engaging with the car, a sliding or reciprocating frame or bar, a yielding or pivoted hook on said bar for engaging with the car, and connections between said hauling-chain and bar for automatically bringing said car from a state of rest or slow speed by a gradual and continual increased speed to that of the chain to be caught and hauled thereby. 65
17. A device for moving cars, consisting of a hauling-chain having hooks on one side thereof for engaging with the car, hooks on the opposite side of said chain, a sliding or reciprocating frame or bar, a yielding or pivoted hook on said bar for engaging with the car, and connections between the hooks on the opposite side of said chain from the car-engaging hooks and the bar for bringing said car from a state of rest or slow speed by a gradually-increased speed to that of the chain to be caught and hauled thereby. 70
18. A device for moving cars, consisting of a hauling-chain having hooks on one side thereof for engaging with the car, hooks on the opposite side of said chain, a sliding or reciprocating frame or bar, a yielding or pivoted hook on said bar for engaging with the car. 75

car, and connections between the hooks on the opposite side of said chain from the engaging hooks and the bar for automatically bringing said car from a state of rest or slow speed by a gradually-increased speed to that of the chain to be caught and hauled thereby.

19. A device for moving cars, consisting of a hauling-chain having hooks on one side thereof for engaging with the car, hooks on the opposite side of said chain, a sliding or reciprocating frame or bar, a yielding or pivoted hook on said bar for engaging with the car, and connections between the hooks on the opposite side of said chain from the car-engaging hooks and the bar for bringing said car from a state of rest or slow speed by a gradual and continual increased speed to that of the chain to be caught and hauled thereby.

20. A device for moving cars, consisting of a hauling-chain having hooks thereon for engaging with the car, hooks on the opposite side of said chain, a sliding or reciprocating frame or bar, a yielding or pivoted hook on said bar for engaging with the car, and connections between the hooks on the opposite side of said chain from the car-engaging hooks and the bar for automatically bringing said car from a state of rest or slow speed by a gradual and continual increased speed to that of the chain to be caught and hauled thereby.

21. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, and means connected to one of said wheel-shafts for engaging with the hooks on the opposite side of the chain from the car-engaging hooks and with the bar for bringing said car from a state of rest or slow speed by a gradually-increased speed to that of the chain to be caught and hauled thereby.

22. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, and means connected to one of said wheel-shafts for engaging with the hooks on the opposite side of the chain from the car-engaging hooks and with the bar for automatically bringing said car from a state of rest or slow speed by a gradually-increased speed to that of the chain to be caught and hauled thereby.

23. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, and means connected to one of said wheel-shafts

for engaging with the hooks on the opposite side of the chain from the car-engaging hooks and with the bar for bringing said car from a state of rest or slow speed by a gradual and continual increased speed to that of the chain to be caught and hauled thereby.

24. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, and means connected to one of said wheel-shafts for engaging with the hooks on the opposite side of said chain from the car-engaging hooks and with the bar for automatically bringing said car from a state of rest or slow speed by a gradual and continual increased speed to that of the chain to be caught and hauled thereby.

25. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, a cam-drum loosely mounted around one of said wheel-shafts having an arm connected thereto for engaging with the hooks on the opposite side of said chain from the car-engaging hooks, and ropes connected to drums and to the said cam-drum and said bar for bringing said car from a state of rest or slow speed by a gradually-increased speed to that of the chain to be caught and hauled thereby.

26. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, a cam-drum loosely mounted on one of said wheel-shafts having an arm connected thereto for engaging with the hooks on the opposite side of said chain from the car-engaging hooks, and ropes connected to drums and to the said cam-drum and said bar for automatically bringing said car from a state of rest or slow speed by a gradually-increased speed to that of the chain to be caught and hauled thereby.

27. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, a cam-drum loosely mounted on one of said wheel-shafts having an arm connected thereto for engaging with the hooks on the opposite side of said chain from the car-engaging hooks, and ropes connected to drums and to said cam-drum and said bar for bringing said car from

a state of rest or slow speed by a gradual and continual increased speed to that of the chain to be caught and hauled thereby.

28. A device for moving cars, consisting of a hauling-chain passing around wheels mounted on shafts, hooks on one side of said chain for engaging with the car, hooks on the opposite side of said chain, a sliding or reciprocating frame or bar, a yielding or pivoted hook on said bar for engaging with the car, a cam-drum loosely mounted on one of said wheel-shafts having an arm connected thereto for engaging with the hooks on the opposite side

of said chain from the car-engaging hooks, and ropes connected to drums and to said cam-drum and said bar for automatically bringing said car from a state of rest or slow speed by a gradual and continual increased speed to that of the chain to be caught and hauled thereby.

In testimony whereof I, the said ALFRED M. ACKLIN, have hereunto set my hand.

ALFRED M. ACKLIN.
